VACUUM TUBE

Filed Nov. 28, 1927

UNITED STATES PATENT OFFICE

EDMUND GUYER MURPHY, OF CHICAGO, ILLINOIS

VACUUM TUBE

Application filed November 28, 1927. Serial No. 236,260.

My present invention, which is an improvement over that disclosed in my Patent No. 1,699,011, for vacuum tubes, dated January 15, 1929, for improvements in vacuum tubes, relates to improvements in wireless receiving and transmitting apparatus, and more particularly to vacuum or electron tubes of the type suitable for receiving and transmitting electrical oscillations.

10 The object of the invention is to provide an apparatus of the kind described that will be more efficient in receiving and transmitting electrical oscillations.

Another object is to provide a vacuum tube 15 wherein is incorporated a novel combination of individually selective amplifying and detecting elements.

A further object of the invention is to provide means in a vacuum tube augmenting in 20 practically two-fold ratio its receiving and transmitting powers without the necessity of additional apparatus.

Other objects and advantages of the 25 method and construction employed will appear more fully in the hereinafter specification when taken in connection with the accompanying drawings in which.

Fig. 1 is a side elevation of a vacuum tube embodying my invention.

30 Fig. 2 is a vertical section taken on line 2-2 of Fig. 1.

Fig. 3 is an enlarged longitudinal section of the novel insertible thermionic valve B.

Fig. 4 is a longitudinal section of the glass 35 envelope of the thermionic valve B before the insertion of the electrodes therein and the sealing of the envelope by the fusing of the glass cap therein.

Fig. 5 is a perspective view of the anode 40 electrode used in the insertible thermionic valve B.

Fig. 6 is a vertical section of my device 45 with the insertible valve B in operative position, the cathodes of tube A and valve B being connected in parallel; parts of tube A being broken away, while valve B is illustrated in elevation.

Fig. 7 is a view similar to Fig. 6, showing 50 all of the electrodes of tube A and valve B

connected in parallel, the transformer being removed from valve B.

With more particular reference to the drawings wherein similar characters of reference indicate corresponding parts in the several views of the preferred form of my invention, A designates a vacuum tube, having the envelope 11 with the integral press 12 adapted to support the electrodes of the tube, comprising the cathode 13, cathode supporting rod 13', grid 14, grid lead 14', anode 15 and the resilient contact 16 connected to grid lead 14'. 17 designates the base of the tube A having the orifices 18 wherein are crimped or otherwise suitably secured the metal tubular sections 19 and 20 accommodating the insertible, three electrode thermionic valve B on which is wound the transformer C forming a part thereof. In the base of the tube A are also secured the exterior cathode prongs 21, 22 and the grid and anode prongs 23 and 24, respectively.

The envelope of the novel thermionic valve and transformer combined B-C, comprises 75 a glass tube 25 and a cap 25' therefor, having reentrant, axially positioned, tubular projections 26 26' with flares 27 27' and stems 28 28', the latter being adapted to provide a seat for one end of a control grid 29 which has a connection 30 to an outside collar 31 seated in one of the circumferential grooves 32, the under side of which form bulges 33 on the inside wall of the envelope to serve as anchorages against longitudinal slippage of the tubular anode 34,—the anode 34 being formed of a sheet of aluminum, nickel, copper or other suitable metal, wrapped into a roll and then permitted to expand against the sides of the glass envelope 25 behind the circumferential bulges 33,—the tongue 34' of the anode being protruded through one of the apertures 35 in the bulges 33 and soldered or otherwise suitably secured to the collar 36 which is connected to the primary 37 of the transformer C.

Through the axial openings 36' 36 in the tubular reentrant projections 26 26' of the envelope 25 and cap 25' is stretched the cathode 38, the ends of which are secured in the glass envelope and cap by fusing of the 100

glass,—the cap 25' being fused to the inner side of the envelope 25 after the insertion of the electrodes therein by a method herein-after described in detail. Metal caps 39 and 40, soldered to the ends of the cathode 38, are cemented to the sealed glass envelope 25 and the cap 25', completing the tube B shown in Fig. 3.

Upon the insertion of tube A into a conventional tube socket with suitable sources of cathode, grid and anode electrical energy connected thereto, the cathode circuits will be completed through prong 22, wire 41, metal tube section 18, metal cap 40 of tube B, through cathode 38, metal cap 39, metal tube section 19, cathode supporting rod 18', cathode 13 of tube A to prong 21,—the cathodes of tube A and thermionic valve B, in this instance, being energized in series.

Electrical oscillations may be superimposed on the grid 29 of valve B via the prong 23, resilient contact 23', metal collar 31 and inside connecting lead 30 to grid 29. Potential for the anode 34 of tube B, as illustrated in Fig. 2, is impressed through prong 24, resilient contact 24' which may be of comparatively high resistance in order to obtain a drop of potential thereacross for a purpose that will hereinafter appear, through primary 37 of transformer C, to anode 34.

The output of valve B, which in Fig. 2, is a "soft" or gas filled tube, and in Fig. 6, is a tube of high vacuum, is impressed on the high vacuum amplifying tube in the usual manner employed in cascade amplification. The secondary 37' of transformer C receives the output current of thermionic valve B by inductive coupling from the primary 37, the resilient contact prong 16 of tube A conveying the current via grid lead 14' to grid 14,—an amplified thermionic current flowing in the circuit of the anode 15 of tube A. The grid return for tube A is made through contact 23'' which is integral with prong 23', the latter prong being preferably of higher resistance than contact 23'' for the purpose of securing a drop of potential thereacross.

Inductive feedback or regeneration in tube B is obtained by means of the transformer C, the stronger oscillations in the circuit of the anode 34 being inductively reimpressed on the secondary 37' of the transformer C connected to grid 29 via contacts 23'', 23', collar 31 and connection 30,—thereby reinforcing the original grid potential, the reinforced grid oscillations being recoupled to the anode,—the cycles repeating until a maximum anode current is built up in an inappreciable space of time, in the manner well known. By sliding valve B transversely, the degree of regeneration may be varied as the valve B is slid to a greater or less extent. By an inspection of the electrodes of tube A and the circuits connected therewith, it will be seen that regeneration in tube A occurs simul-

taneously with that secured in the valve B,—the primary 37 of transformer C being connected to anode 34 of valve B and to anode 15 of tube A, while secondary 37' is connected to grid 29 of valve B and to grid 14 of tube A,—the process of circuit regeneration then taking place in tube A simultaneously and in a manner similar to that described with reference to valve B. The potentials impressed on grids 14 and 29 of tube A and valve B respectively, it will be observed, are made variable by the sliding of valve B transversely.

The collar 31 on valve B, which here, for the purpose of illustration, is shown of comparatively small width, is preferably in practice made slightly wider with a view to permitting the resilient contact 23' to engage same slidingly when the valve B is thrust transversely, carrying the primary 37 and the secondary 37' over the prongs 24' and 23'.

The anode 15 of tube A, as shown in Fig. 2, is connected to the same source of potential as anode 34 of valve B, but in the particular form illustrated, is preferably, for the purpose of amplification, impressed with a higher potential than the anode of valve B, this result being readily obtained by the use of a high resistance in the resilient contact 24'. By this means, I obtain a drop of potential across the contact 24', this being desirable when tube A is used as the amplifying tube. When the tube A is of the gas filled type for use as a detector, the lead 41, on the contrary, may be of sufficient resistance to cause a drop of potential thereacross with respect to anode 15,—the anode 34 of valve B in this instance receiving a higher impressed voltage under circumstances deemed desirable.

In Fig. 6, the mode of energizing the separate cathodes of tube A and valve B in parallel, is shown. Herein the cathode prong 21 is merely wired to metal tube section 19 via the lead 21', while the cathode prong 22 is connected to opposite metal tube section 18,—all other connections being identical with those shown in Fig. 2. The method employed in my device as shown in Fig. 6 is generally preferable to that disclosed in Fig. 2, since in the former, the cathodes being wired in parallel, there will be no necessity of reducing the voltage across the cathode of tube A should it be desired to withdraw the thermionic valve B. The drop of potential that occurs when the cathodes of vacuum tubes are wired in series, however, offers well known advantages where it is desired to supply electrical energy at a comparatively high voltage and small amperage. With the slight change in the wiring indicated, either method may be employed for operating the cathodes in series or parallel.

In the process of manufacture of the thermionic valve B, the grid 29 is first inserted in the envelope 25 and connection 30 passed through slot 35 in the bulge 33; the anode 34

is next inserted in the envelope in the form of a roll and allowed to expand against the sides of the tube 25 in the manner illustrated in Fig. 3, the tongue 34' of the anode being protruded through the other slot 35,—the cathode 38 is now passed through the reentrant projections 26 and 26' of the tube and cap respectively, the latter now being applied. The opening 36' and the slots 35 are fused, the glass cap 25' inserted in the envelope 25 and fused thereto. The envelope 34 is now evacuated through opening 36" which is immediately sealed by fusing upon the completion of the evacuation. The collar 31 is then applied and soldered to the lead wire 30, the tongue 34' to primary 37, the ends of the cathode 38 soldered to the two metal caps 39, 40 which are now permanently affixed to the glass envelope by cementing. This completes the manufacture of valve B.

The dual thermionic valve herein described and illustrated is exceedingly flexible in adapting itself to a wide variety of uses such as; a combined detector and audio frequency oscillation amplifier, a combination radio frequency oscillation amplifier and a detector of oscillations, a combination two tube radio or audio frequency oscillation amplifier. It is also within the province of my invention to connect all the electrodes of tube A and valve B in parallel by merely removing the transformer C and placing contact 24' on collar 36 and the resilient contact 16 on collar 31. The use of vacuum tubes wired in parallel to handle a heavy current output in the last audio stage of multiple tube receiving sets, and particularly in commercial radio transmitting apparatus where it is desirable to radiate a comparatively heavy amperage from the antenna circuit, presents marked advantages over the wiring of tubes in series. My novel combination tube and thermionic valve when wired in parallel, by its economy of space and interchangability is particularly adapted to this method of wiring.

The transformer C wound on the exterior of the thermionic valve B, it is also to be noted, by electro-magnetic induction, exerts a well known modifying effect on the electronic stream from the cathode and on the currents in the circuits of the grid and anode of the thermionic valve.

While I have herein described and in the accompanying drawings illustrated a preferred embodiment of my invention, I do not thereby desire nor intend to limit myself specifically thereto as it will be understood that the device is susceptible of the widest variation and modification within the scope of the invention as defined in the appended claims.

What I claim as new and desire to secure by Letters Patent is:

1. An electro-responsive device comprising, in combination, a plurality of thermionic valves, one of said thermionic valves being

electrically connected to the second of said thermionic valves and inclosed in means mechanically fastened to the exterior of said second valve.

2. An electro-responsive device comprising a vacuum tube having a plurality of electrodes, and thermionic means removably insertible within the base of said vacuum tube whereby said plurality of electrodes may be energized through said means.

3. A vacuum tube having a plurality of electrodes, and means including a thermionic member within the base of said vacuum tube whereby a variable potential may be impressed upon at least one of said plurality of electrodes.

4. An electro-responsive device comprising a vacuum tube, and means mechanically and electrically connected to said vacuum tube and a thermionic valve, removably and adjustably mounted in said means to serve as a medium through which said vacuum tube may be energized.

5. A vacuum tube having a plurality of electrodes, and thermionic means removably insertible within the base of said vacuum tube and means whereby said plurality of electrodes may be impressed with the output of said thermionic means.

6. A vacuum tube comprising, in combination, an envelope containing a plurality of electrodes, a base secured to said envelope, a thermionic valve within said base operatively connected to said electrodes, means whereby said electrodes and said thermionic valve may be simultaneously energized and deenergized, and means whereby the current output of said thermionic valve may be impressed on said electrodes.

7. In combination, a plurality of individual vacuum tubes of dissimilar type operatively connected together, a socket in the base of one of said tubes, the other of said vacuum tubes being removably embodied within said socket.

8. An electro-responsive device comprising, in combination, an amplifying vacuum tube, means within the base of said amplifying vacuum tube to operatively receive therein a gaseous thermionic valve, and means whereby the electrical output of said gaseous thermionic valve can be impressed on said vacuum tube.

9. An electro-responsive device comprising, in combination, a vacuum tube and removable means within the base of said vacuum tube whereby circuit regeneration may be obtained.

10. An oscillation responsive device comprising, in combination, a vacuum tube including cathode, anode and grid electrodes, and adjustable electro-magnetic means within the base of said tube whereby electrical oscillations impressed on the anode circuit from the grid circuit of said vacuum tube may

be reimpressed on said grid circuit and thence back again on said anode in cycles, whereby circuit regeneration in said vacuum tube is secured.

11. An electro-responsive device comprising, in combination, a vacuum tube having cathode, anode and grid electrodes, a thermionic valve within the base of said vacuum tube, said thermionic valve having cathode, anode and grid electrodes, means to impress the potential of the thermionic valve on the vacuum tube, and additional means within the base of the vacuum tube whereby circuit regeneration of both the vacuum tube and the thermionic valve is simultaneously obtained.

12. An electro-responsive device comprising, in combination, a vacuum tube having a plurality of electrodes, a thermionic valve within the base of said vacuum tube, means to impress the potential of said thermionic valve on the electrodes of said vacuum tube, and means whereby the current output of said vacuum tube and said thermionic valve are combined together within the base of said vacuum tube.

13. An electro-responsive device comprising, in combination, a vacuum tube having a plurality of electrodes, a thermionic valve within the base of said vacuum tube, said thermionic valve having a plurality of electrodes, additional means within the base of said vacuum tube whereby the said electrodes of both the vacuum tube and the thermionic valve may be simultaneously energized and deenergized, means whereby the output potential of said thermionic valve may be impressed on said vacuum tube, and means whereby the combined electrical output of both the vacuum tube and the thermionic valve may be obtained from a contact element on the exterior of said vacuum tube.

14. An electro-responsive device comprising, in combination, a plurality of thermionic valves, each of said valves having cathode, anode and grid electrodes, one of said valves being operatively housed within the base of and operatively connected to the other of said thermionic valves, and means mounted on one of said thermionic valves whereby oscillation regeneration in the circuits of the electrodes of both of said thermionic valves is simultaneously obtained.

15. An electro-responsive device comprising, in combination, a plurality of thermionic valves, one of said thermionic valves being wound with an inductance and being removably insertible within the base of the other of said thermionic valves, and means whereby circuit regeneration in the electrodes within each of said thermionic valves and the circuits connected therewith is simultaneously obtained by means of said inductance.

16. A thermionic valve comprising a tubular envelope, cathode, grid and anode electrodes individually supported within said en-

velope, said anode electrode consisting of a sheet of metal rolled into a resilient roll and then permitted to expand against the interior circumference of said envelope, and a transformer wound on the exterior of said envelope and having connections to the grid and anode electrodes therein, whereby regeneration in the circuits connected to said grid and anode electrodes may be obtained.

17. A thermionic valve in the form of a cartridge, said thermionic valve being removably and adjustably insertible within the base of a vacuum tube, means whereby said vacuum tube may be energized and deenergized through said thermionic valve, means whereby potentials of unequal strength may be simultaneously impressed on the grid and anode electrodes of both the thermionic valve and the vacuum tube and means whereby regeneration in the circuits connected with the said grid and anode electrodes is obtained.

18. An electro-responsive device comprising, in combination, a vacuum tube, a thermionic valve within the interior of means fastened to said vacuum tube and operatively wired in parallel therewith, and other means connected to the exterior of said vacuum tube whereby said vacuum tube and said thermionic valve may be simultaneously energized and deenergized.

In testimony whereof I have signed my name to this specification.
